CUTTER

Virgil H. Baker, Springfield, Ohio, assignor to
 Elliott Company, Pittsburgh, Pa., a corporation
 of Pennsylvania

Application June 19, 1939, Serial No. 279,832

10 Claims. (Cl. 15—104.13)

This invention pertains to new and improved cutters, and more particularly, to improved cutters for tube cleaning such as are employed in removing scale, carbon, etc., from interiors of boiler or oil refinery tubes.

In removing deposits from the inside of tubes or pipes, relatively high speed rotating cutter heads equipped with cutter wheels are employed. Since the teeth of the cutter wheels are milled to a sharp edge and are thrown at a high speed against the walls of a tube by centrifugal force, a grinding action is created which removes a deposit from the tube. It will be apparent that internal abrasion is unavoidable and thus must be kept at a minimum at all times. Such abrasion is particularly serious in oil refinery applications where alloy tubes are used and are quite expensive from the standpoint of original cost, maintenance, and replacement. It is customary to caliper the tubes in oil refinery applications on the inside after each cleanout; the tubes are generally of extended length and are fully calipered along such length in order to determine the wall thickness. The tubes are removed when the thickness reaches a minimum for the pressure under which they operate. It is difficult to accurately caliper the inside of a tube having an irregular surface, with the result that the operator may be misled as to the actual thickness; rupture causes serious damage.

Rough and deep indentations on the inside of tubes are also undesirable due to the more rapid accumulation of deposit and the difficulty of thereafter cleaning the tube. Small particles gather in such irregularities and continue to build up until the flow is obstructed.

Heretofore, considerable difficulty has been encountered in devising a suitable type of cutter for eliminating the so-called gear or track effect. In view of the above considerations, it has been an object of my invention to provide a new and improved form of cutter that effects a substantially smooth track on the surface being cleaned.

Another object of my invention has been to provide an inexpensive and practical form of cutter for the purposes enumerated.

A further object has been to determine the factors that govern the type of grinding action effected upon the surface being cleaned.

These and many other objects of my invention will appear to those skilled in the art in view of the description, the drawing, and the appended claims.

Figure 1 is a side elevation of a tube cleaner having cutters embodying my invention;

Figure 2 is a side view and Figure 3 is an end view in elevation of a cylindrical type of cutter embodying my invention;

Figure 4 is a side view similar to Figure 2, but showing a frusto-conical type of cutter embodying the principles of my invention;

Figure 5 is an end view similar to Figure 3 but showing a modified type of tooth arrangement;

Figure 6 is an enlarged perspective section illustrating a track or gear effect that may be produced upon the inside of a tube being cleaned by an ordinary type of cutter; and

Figure 7 is an enlarged perspective section similar to Figure 6, but showing an improved effect that may be accomplished by a cutter embodying the features of my invention.

As will be appreciated from a study of Figure 6, the progressive action of the teeth of an ordinary type of cutter will cut complementary gear-like indentations that correspond to the cutting face of the cutters being employed. I have discovered that a cutter having cutting teeth of equal space will strike the tube at approximately the same place with each rotation and that this results in the track or groove cutting before mentioned. I have been able to eliminate this effect, to minimize the cutting action, and to provide a relatively smooth cut surface by employing a series of substantially uniformly spaced teeth with one exception. In other words, I provide an additional spacing between one pair of adjacent teeth that is not uniform as compared with the spacing of the others. In this connection, I have found that the desired effect is also insured by employing an uneven or an odd number of teeth.

I have also determined that in addition to employing an odd number of teeth, it is preferable to provide an odd fractional spacing between a pair of teeth to obtain the most effective results. In this connection, I have found an odd fraction of a third to be very satisfactory.

In Figure 1, 10 shows a suitable type of cleaning head providing with frusto-conical cutters 11 and cylindrical cutters 12 constructed and arranged in accordance with the principles of my invention. Figures 2 and 3 show the cylindrical form of cutters 12 while Figure 4 shows a frusto-conical type 11; as shown, both types are provided with additional spacing 13 and an odd number of teeth.

In making a no-track cutter, I preferably divide the periphery of the cutter head into an evenly distributed number of spaces. And, on the final cut, the divided head is so arranged that it

advances the work in such a manner that the groove as now cut by the milling cutters is advanced by a space that is larger by a fraction, preferably by a third, than the preceding spaces measured on any symmetrical arc.

As will be appreciated from a comparison of Figures 6 and 7 of the drawing, a cutter constructed in accordance with my invention is also much more efficient, particularly in cleaning out hard, brittle, or coke-like substances; as random chisel-like blows are very effectively delivered and less power is required. On the other hand, an ordinary type of cutter provides less freedom for removal of the chips, and its impact is delivered over deep cuts that not only consume greater power, but in effect, provide a "follow-track" that makes it difficult to cut adjacent "hill" portions of an encrustation.

The preferred arrangement comprises an odd number of teeth and a spacing between a pair of teeth that is non-uniform compared with the spacing between others. In a broader aspect, the invention pertains to a cutter having a series of teeth of substantially uniform peripheral dimension, which peripheral dimension comprises the width and spacing of the teeth, and additionally preferably having at least one tooth or an odd number of teeth of non-uniform dimension in this respect. As shown in Figure 3, the dimension *a* is non-uniform or greater than the dimension *b* of the uniform-dimension series of teeth. This is true regardless of whether a wider spacing 13 is provided or whether the tooth is provided with a greater width, see the line *c* of Figure 5.

In carrying out the invention, I have found that the number of odd spaces is relatively unimportant provided the aggregate increase of each space equals substantially one-third of the uniform space. One space, for example, can be formed substantially one-third less in width than the other uniform spaces to obtain the trackless results.

It is believed one of the important features of the present invention rests in the provision of a cutter element having a series of substantially uniformly spaced cutting teeth about the periphery thereof with a spacing between at least one pair of teeth being non-uniform and having a width differing from the uniform spacing by an odd fractional amount taken, for example, from the series beginning one-third, one-sixth, etc. Also in accordance with my invention, it is important that the total width of non-uniform spacing should be such that the aggregate must not total an even space but should differ from the even or uniform spacing by a fractional amount such as represented by the above odd fractional series of one-third, one-sixth, etc. Stated somewhat differently, the spacing between at least one pair of teeth is preferably non-uniform with respect to and having a width differing from the uniform spacing of the majority of the teeth; this difference of width being an amount substantially equal to one-third of the uniform spacing divided by an integer.

Although for the purpose of describing my invention, I have shown certain forms thereof, it will be apparent to those skilled in the art that other suitable forms may be employed and that suitable modifications, substitutions, additions, etc., may be exercised without departing from the spirit and scope of the invention as indicated by the appended claims.

I claim:

1. In a tube cleaner, a cutter element operably associated therewith, said cutter element having a series of substantially-uniformly spaced cutting teeth about the periphery thereof, the spacing between a pair of teeth being non-uniform and having a different width than said above-mentioned uniform spacing.
2. In a tube cleaner, a cutter element operably associated therewith, said cutter element having a series of substantially-uniformly spaced cutting teeth about the periphery thereof and having a tooth non-uniformly spaced with respect to another tooth and having a greater width of spacing than said above-mentioned uniform spacing.
3. In a tube cleaner, a cutter element operably associated therewith, said cutter element having a series of cutting teeth of substantially-uniform-peripheral dimension comprising teeth width and spacing and having a tooth of non-uniform peripheral dimension comprising tooth width and spacing.
4. In an article of manufacture for trackless tube cleaning, a cutter element having a plurality of teeth about its periphery, said cutter element having a tooth whose spacing with respect to an adjacent tooth is different than the spacing between other teeth, such other teeth having a substantially uniform spacing with respect to each other, and being of substantially the same radial length.
5. In an article of manufacture for trackless tube cleaning, a cutter element having a plurality of cutting teeth about the periphery thereof, said cutting teeth being an odd number, at least a portion of said teeth having a substantially uniform spacing therebetween, the spacing between a minority of said teeth being different than the spacing between other teeth, all of said teeth being of substantially the same radial length.
6. In a tube cleaner, a cutter element operably associated therewith, said cutter element having a series of substantially-uniformly spaced cutting teeth about the periphery thereof, the spacing between at least one pair of teeth being non-uniform and having a width differing from said above-mentioned uniform spacing by an amount substantially equal to one-third of the uniform spacing, divided by an integer.
7. In a tube cleaner, a cutter element operably associated therewith, said cutter element having a series of substantially uniformly spaced cutting teeth about the periphery thereof, the spacing between at least one pair of teeth being non-uniform and having a width differing from said above-mentioned uniform spacing by a fractional amount of substantially one-third.
8. In a tube cleaner, a cutter element operably associated therewith, said cutter element having cutting teeth, a majority of said cutting teeth being of substantially uniform peripheral dimension comprising teeth width and spacing, and a minority of said teeth being of substantially non-uniform peripheral dimension comprising teeth width and spacing.
9. In an article of manufacture for tube cleaning, a cutter element having a series of substantially uniformly spaced cutting teeth about the periphery thereof, said cutter element also having at least a pair of cutting teeth about the periphery thereof having a substantially non-uniform spacing therebetween, all of said cutting teeth having substantially the same radial length,

the total non-uniform spacing having a different width than the uniform spacing.

10. In an article of manufacture for tube cleaning, a cutter element having a series of substantially uniformly spaced cutting teeth about the periphery thereof, said cutter element also having at least a pair of cutting teeth about the

periphery thereof having a substantially non-uniform spacing therebetween, the total non-uniform spacing having a different width than the uniform spacing, said cutter element having an odd number of teeth about its periphery.

VIRGIL H. BAKER.
